UNITED STATES PATENT OFFICE

MORTON HAGUE, OF CHICAGO, ILLINOIS

DESIGN FOR A SHRINE

Application filed April 4, 1932. Serial No. 43,386. Term of patent 14 years.

To all whom it may concern:

Be it known that I, MORTON HAGUE, a citizen of the United States, residing at 105 East Delaware Place, Chicago, in the county of Cook and State of Illinois, have invented a new, original, and ornamental Design for a Shrine, of which the following is a specification, reference being had to the accompanying drawing, forming a part thereof.

The figure is a perspective view of a shrine, embodying my new design.

I claim:

The ornamental design for a shrine substantially as shown.

MORTON HAGUE.
